COMBINATION SEED PACKAGE AND
GARDEN MARKER

Oliver H. Roskam, R.R. 4, Parkville, Mo.

Original design application Aug. 5, 1963, Ser. No. 76,101,
now Design Patent No. 199,032, dated Sept. 1, 1964.
Divided and this application July 21, 1964, Ser. No.
80,943

Term of patent 14 years

(Cl. D35—1)

Fig.1.

Fig.2.

Fig.3.

FIG. 1 is a front elevational view of a combination seed package and garden marker showing my new design; FIG. 2 is a rear elevational view thereof; and

FIG. 3 is a sectional view taken on line 3—3 of FIG. 1 of the combination seed package and garden marker.

This application is a division of application Serial No. 76,101, filed August 5, 1963, now Patent Number D. 199,032.

I claim:

The ornamental design for a combination seed package and garden marker, as shown.
